UNITED STATES PATENT OFFICE.

JOHN HOLLAND LETZ, OF CROWN POINT, INDIANA, ASSIGNOR TO THE LETZ MANUFACTURING COMPANY, OF CROWN POINT, INDIANA, A CORPORATION OF INDIANA.

GRINDING-BUR.

1,181,231.

Specification of Letters Patent.

Patented May 2, 1916.

Application filed February 7, 1916. Serial No. 76,506.

To all whom it may concern:

Be it known that I, JOHN HOLLAND LETZ, a citizen of the United States, and a resident of Crown Point, in the county of Lake 5 and State of Indiana, have invented certain new and useful Improvements in Grinding-Burs, of which the following is a full, clear, and exact specification.

My invention is concerned with improvements in grinding burs of the type shown 10 in the Letz Patent No. 437,699, dated October 7, 1890, in which a disk having a generally flat face has formed thereon a series of main ribs from which short opposed branch ribs diverge at intervals, the tops of 15 said ribs being ground flat and serving as cutting or shearing edges when coöperating with the similar ribs of the companion bur in grinding grain or other materials.

20 My invention consists in a change in the configuration of the ribs, whereby the capacity of the grinding mill employing them can be increased, and the amount of friction reduced.

25 To illustrate my invention, I annex here-to a sheet of drawings in which the same reference characters are used to designate identical parts in all the figures, of which—

Figure 1 is a plan view of a section of a 30 bur embodying my invention; Fig. 2 is a similar view of a larger section with portions of the companion bur superposed thereon to indicate the relationship of the ribs; and Fig. 3 is a cross-section on a large scale 35 on the line 3—3 of Fig. 1.

As these burs are ordinarily constructed, the stationary bur, at any rate, has a centrally receiving aperture, so that the general shape of the bur is that of an annulus. 40 As seen in cross-section in Fig. 3, this annulus consists of a body portion *a*, the upper surface of which is generally flat, although it is preferably slightly inclined at *b* on the interior of the grinding surfaces. I may 45 employ a pair of annular flanges *c* on the reverse face, but my invention is concerned with the design of the ribs which are shown as raised a slight distance above the flat surface of the part *a*, and as having their upper surfaces ground off flat, so as to form 50 shearing edges. It will, of course, be understood that these burs are preferably formed by casting them, and that after they are cast, it is an extremely simple operation

to grind off the rough outer edges of the 55 cast ribs into a series of perfectly flat surfaces, all lying in the same plane.

By reference to the various figures, it will be obvious that the ribs are arranged in groups in which the same design is repeated, each group covering a certain number of degrees, for instance, 30, of the entire surface of the disk. In the configuration of the aforesaid Letz Patent No. 437,699, each group of ribs is made up of a plurality of 60 main ribs with short opposed branches extending therefrom, the main ribs of a group successively decreasing in length and the branch ribs projecting into the paths formed by the parallel main portions of the ribs to 65 70 form a tortuous passage for the grain from the center to the periphery of the disks. As indicated in Fig. 2, the ribs on the two burs, when placed in juxtaposition, extend substantially across each other at right angles, 75 and as the moving bur is rapidly rotated, the material fed between them passes by the centrifugal action out through the tortuous passages thus formed, and is discharged from the peripheries of the burs. The 80 passages formed by the ribs fill up with the grain, and any grains or particles wider than the depth of the passages are sheared off by the cutting edges of the ribs as they pass each other.

85 Referring now especially to Figs. 1 and 2, the set of ribs corresponding to a long rib and its branches of the bur of the aforesaid Letz Patent No. 437,699, consist of three main ribs *1^a*, *2^a*, and *3^a*, and three 90 smaller ribs *4^a*, *5^a* and *6^a*. The main ribs *1^a* and *2^a* will be seen to consist of the inner portion which extends at an acute angle to an adjacent radial line, and of an outer portion which extends substantially parallel to said radial line. The ribs *4^a* and *3^a* will be seen to constitute continuations, as it were, of the line formed by the inner portions of the ribs *1^a* and *2^a*. The ribs *5^a* and *6^a* will be seen to extend away substantially at right angles to the angles of the ribs *1^a* and *2^a*, being separated therefrom, as shown. This general design corresponds to a long rib and its branches of the aforesaid Letz Patent No. 437,699, if sections were cut out therefrom at the points where the branches occur. Similarly, the ribs *1^b*, *2^b*, *4^b*, *5^b* and *6^b* correspond to the 95 100 105

next shorter rib and its branches of the aforesaid Letz patent, with the same sections removed. Likewise, the ribs 1°, 2°, 4°, 5° and 6° correspond to the next shorter rib 5 and its branches of the original Letz patent, and so on. With this new configuration of the ribs I find that the capacity of the mill is materially increased without destroying in the least the fineness of the 10 grinding, this increased capacity probably being due to the grain being free to pass in a more nearly radial line between the burs by passing through the cut-away portions. In the matter of reduced friction, I find 15 that this is also very perceptible, and this reduced friction probably results from the reduction of the large triangular surfaces found in the original Letz patent, where the branch ribs unite with the main rib, and as 20 the ribs are ground down in use, the areas of these triangular surfaces increase, increasing the friction. With so much of these large triangular surfaces cut away as occurs in the new construction, this friction 25 is very materially reduced.

What I claim as new and desire to secure by Letters Patent of the United States is:—

1. A grinding bur consisting of a generally flat disk having a series of grinding 30 ribs projecting therefrom and having their flat top surfaces in the same plane and forming shearing edges, said ribs consisting of a plurality of long angular ribs having their main and inner portions extending at 35 acute angles to adjacent radial lines and their outer portions turned substantially parallel to said adjacent radial lines, and a corresponding plurality of short ribs separated from the long ribs and extending 40 away from the angles of the long ribs, sub-

stantially at right angles to the outer portions thereof.

2. A grinding bur consisting of a generally flat disk having a series of grinding ribs projecting therefrom, and having their 45 flat top surfaces in the same plane and forming shearing edges, said ribs consisting of a plurality of long angular ribs having their main and inner portions extending at acute angles to adjacent radial lines 50 and their outer portions turned substantially parallel to said adjacent radial lines, and a corresponding plurality of short ribs separated from the long ribs and extending away from the angles of the long ribs, substantially 55 at right angles to the outer portions thereof, the main portions of pairs of the long ribs being in alinement but not touching, and said pairs being grouped with others that are parallel, substantially as 60 shown and described.

3. A grinding bur consisting of a generally flat disk having a series of grinding ribs projecting therefrom and having their flat top surfaces in the same plane and forming shearing edges, said ribs consisting of a plurality of long angular ribs having 65 their main and inner portions extending at acute angles to adjacent radial lines and their outer portions turned substantially 70 parallel to said adjacent radial lines, and a corresponding plurality of short ribs extending away from the angles of the long ribs, substantially at right angles to the 75 outer portions thereof.

In witness whereof, I have hereunto set my hand and affixed my seal, this 3rd day of February A. D. 1916.

JOHN HOLLAND LETZ. [L. S.]
